[57] CLAIM

The ornamental design for a skate sling carrier, as shown and described.

DESCRIPTION

FIG. 1 is a front elevational view of a skate sling carrier, showing my new design;

FIG. 2 is a side elevational view, the opposite side being a mirror image thereof;

FIG. 3 is a rear elevational view thereof;

FIG. 4 is a top plan view thereof; and,

FIG. 5 is a bottom plan view thereof.
